SPRING CUSHION CONSTRUCTION

Clair S. Reed, Jackson, Mich., assignor to Reynolds Spring Company, Jackson, Mich., a corporation of Delaware

Application April 4, 1938, Serial No. 199,887

7 Claims. (Cl. 155—179)

The present invention relates to improvements in seat and back spring cushion construction, having particular reference to constructions used in vehicles, although suitable for furniture and the like as well.

In designing spring cushions for use in automobiles, for example, a relatively large number of factors must be taken into consideration. The cushion should be yielding so as to possess a soft feeling, yet sufficiently resistant to extreme deflection as to avoid striking "bottom" due to road shock. To afford adequate head room in the automobile it is desirable that the seat cushion have the appearance and feeling of considerable depth, yet be of minimum thickness. In this respect commercial practices up to the present invention have been of a compromising nature. The matter of cost has prevented the use of soft coil springs superimposed upon stiffer coil springs for obtaining a soft upper stratum and a lower weight supporting and shock resisting stratum. Also, in all commercial constructions of which I have knowledge the supporting frames for the cushions have presented a "bottom" encounterable upon extreme deflection or depression of the cushions. In an effort to obtain greater riding comfort with the conventional type of spring cushions the depth of the spring structure and the overhang for leg support and appearance has created a trimming problem which compels actual distortion of the spring structure in order to obtain the desired contours, which for the most part are of a fugitive nature due to the breakdown action normal use has upon the spring and frame structural elements of conventional cushions used in automobiles.

In the patented art appear numerous suggestions of cushion spring constructions which embody some of the elements appearing in the combinations of the present invention. For the most part, these suggestions have as their main object a reduction in the cost of construction through the elimination of coil springs. In most cases the attempt to secure such a result has been made through the use of springs in the form of flattened loops.

According to the present invention in its preferred form, I associate both loop and compression spring elements in a novel manner, providing a cushion which is a substantial improvement over constructions now in use. The cushion is thin, easy to trim, possesses excellent riding qualities and feel, and may be termed as offering a bottomless support. Also illustrated are numerous other forms of the invention in which only loop springs are utilized in the cushion

construction. However, where this type of spring is being used alone I have overcome certain limitations present in similar constructions in the patented art through a novel spring construction and support. Other features of the invention pertain to ventilation of the cushion and the manner in which the seat and back cushions are adaptable to sheet metal and tubular frame structures.

10 To specifically enumerate the various objects of the present invention, one of the objects is to provide a cushion construction embodying loop and compression springs associated in a manner producing relatively thin cushions of improved supporting qualities.

15 Another object is to provide seat and back spring structures for cushions in vehicles, which because of their construction enable the same to be directly supported upon a skeleton seat frame and in a manner making possible a reduction in weight as well as affording improved ventilation.

20 A further object resides in providing a spring cushion structure which may be readily trimmed without distortion, affords adequate support to the trim, and maintains its original untrimmed contour even after extensive service.

25 A still further object resides in a spring cushion constituted as its own supporting frame structure, in which tacking strips have been eliminated and the trim secured in a novel manner.

30 Other objects and advantages of the present invention residing in the arrangement, construction and combination of parts too numerous to be specifically mentioned in the foregoing stated objects will appear from consideration of the following detailed description and the appended claims.

35 In the drawings, wherein a large number of various forms of the invention are illustrated in order that the invention may be clearly understood and the contemplated broad scope of the invention more clearly appreciated.

40 Fig. 1 is a side elevational view of a seat frame embodying cushions constructed in accordance with the present invention.

45 Fig. 2 is a fragmentary front elevational view of a portion of the seat cushion and frame shown in Fig. 1.

50 Fig. 3 is an enlarged detail of a portion of the seat frame and seat cushion shown in broken section in Fig. 1.

55 Fig. 4 is a cross-sectional view of the seat and back cushions associated in the relative positions illustrated in Fig. 1.

Fig. 5 is a fragmentary perspective view of the back cushion spring structure with the trim removed, as shown in Fig. 4.

Fig. 6 is a fragmentary plan view of the spring structure of the seat cushion with the trim removed, as shown in Fig. 4.

Fig. 7 is a cross-sectional view taken on line VII—VII of Fig. 6.

Fig. 8 is a broken cross-sectional view taken on line VIII—VIII of Fig. 6.

Figs. 9, 10 and 11 are fragmentary plan views of modified forms of the stay structure for the transverse loop springs of the spring structure.

Fig. 12 is a fragmentary plan view of another form of arrangement of the loop and compression spring elements.

Fig. 13 is a view similar to Figs. 6 and 9 showing a spring embodying only loop transverse springs.

Fig. 14 is an end view of the construction of Fig. 6 as viewed from the right.

Figs. 15 and 16 are side and plan views, respectively, of the transverse loop spring element of the construction shown in Fig. 7.

Figs. 17 and 18 are side and plan views, respectively, of a modified form of transverse loop spring element.

Figs. 19, 20, 21, 22, 23 and 24 are side elevational views of various forms of loop spring elements particularly designed for seat cushions.

Fig. 25 is a side elevational view of the transverse loop spring element of the back cushion shown in Fig. 4.

Figs. 26 and 27 are side elevational and plan views, respectively, of a modified type of loop spring element similar to that of Fig. 5 to be used in the back cushion of Fig. 1, and

Figs. 28 and 29 are fragmentary side and plan views, respectively, of a combined loop and compression spring, making up a transverse spring element.

Referring to the drawings, in Fig. 1 is shown in side elevation the front seat of an automobile embodying the present invention. It is to be understood, however, that the invention has equal application to rear seats as well. As illustrated, the seat frame comprises a stamped sheet metal base 10 having openwork panels 12 at the front and side to enable air to circulate into the interior. The central upper portion of the base 10 is preferably entirely open, with the exception of a flange 14, which extends entirely around all four sides of the base 10 to support the outer edge portions of the seat cushion 16. The back of the seat frame takes the form of a tubular steel bar 18 of inverted U-shaped contour having the lower ends of the leg portions 20 suitably anchored in sockets at opposite sides of the base 10. As shown, the bar 18 may be described as embedded in the back cushion 22 which it supports.

The spring structure of the back cushion 22, as more clearly shown in Figs. 1, 4, 5 and 25, comprises a plurality of main loop springs 24 each taking the shape of a relatively flat, elongated, closed loop of heat treated spring wire. The front and back central portions 64 and 66 of the springs 24 are preferably undulated in the plane of the supporting surface of the cushion so as to permit deflection without longitudinal shortening, as well as serving to space the coil springs 30 and afford support to the padding and trim. The ends of the spring structure are furnished through the employment of springs 32, 34 and 36, which are generally similar to the

springs 24. These springs have offsets 38 which permit securing the springs in spaced relation through suitable clips 40. For providing the desired contour to the cushion when trimmed or upholstered, each outside spring 36 is shown with straight front and back portions 42 and 44 merging into a return bend 46 which is curved inwardly and clipped at 48 to the spring 34 so as to give a rounded corner when trimmed.

The spacing of the transverse loop springs 24, 32, 34 and 36 is shown to be accomplished through border wires 50, 52 and 54 and a tacking frame member 56 all running longitudinally of the cushion spring structure. For securing the wires 50, 52 and 54 to the transverse springs, the same are formed with offset right angular portions, which are embraced, together with the transverse springs, by clips 58. The tacking frame member 56 may be of any well known construction, being preferably of a fibre filled sheet metal channel with an exposed outer face. Holes are punched along the member 56 to receive fasteners 60, which embrace the loop springs and hold the springs and member 56 in assembled spaced relation by having their ends 62 bent over.

The spring elements 24 are preferably spaced apart a distance slightly in excess of the largest diameter of the terminal coils of the springs 30, the coils 30 being illustrated as of a fabric covered Marshall type. However, other types may be used in lieu thereof, such as cone shape, hour glass shape, etc. As more clearly shown in Fig. 25, the element 24 has a front section 64 and a rear section 66, the latter being offset at 68 to accommodate the bar 18. To provide softness along the lower edge of the back cushion 22, return bend portions 70 and 72 are provided, the latter having a loop 74. Likewise, for providing softness at the top of the cushion, a loop 76 is provided. Preferably the spring elements 24 are fabricated from a continuous strand of steel wire with the ends joined by clips 78. After being shaped as shown in Fig. 25, the spring 24 is then heat treated. As will be understood from Figs. 4 and 5, the springs 30 are suspended from the portions 64 and 66 of the spring elements 24 by hog rings 80 embracing the terminal convolutions of the coil springs 30. Upon deflection of the portions 64 of the spring elements 24, the coils 30 will be compressed. As the resistance of the coils 30 to compression is built up, deflection of the portions 66 will take place. Obviously, the portions 66 can only deflect between their points of support, namely, between the offset 68 supported by the bar 18 and the tacking frame 56, which is supported at its ends on the leg portions 20 of the bar 18. This arrangement gives what may be characterized as a "depthless" action to the central back supporting area of the back cushion 22. In Fig. 1 the offset 68 is shown fastened to the horizontal portion of the bar 18 by a channel clip 82 having its ends clipped over the springs 24 and the sides of the offset 68. It will be noted that the horizontal portion of the rigid bar 18 is located well below the top 84 of the cushion 22, which is a safety feature, as it provides a soft resilient top against which a passenger in the rear seat of the vehicle may be thrown in the event of sudden stoppage without serious injury. To provide a supporting surface for the upholstery along the top 84 of the cushion 22 a mat of mattress wire 86 is anchored along its front edge to a wire 88 and carried over the

top of the cushion and hog ringed to the wire 52 along its back edge. The upholstery 88 is shown covering a padded front surface of the cushion 22, as well as the rear surface, with the opposite ends tacked to the tacking strip 56. The springs 32, 34 and 36 are of substantially the same construction as the spring elements 24, with the exception of the offsets 38 and the fact that the springs 34 and 36 do not have the loop 76 at the top of the cushion.

Referring to Figs. 1-4 and 6-8 of the drawings, the seat cushion is of the same general construction as the back cushion 22. The spring structure comprises transverse loop spring elements 90 having upper and lower portions 92 and 94 preferably undulated in the plane of the supporting surface of the cushion, between which are suspended fabric encased coil springs 96 corresponding to the springs 30. At opposite ends of the spring structure (see Figs. 1 and 6) is a pair of spring elements 98 and 100 of the same general construction as the springs 90. To separate the springs 100 from the outside springs 98 the former are provided with offsets 102 in the upper and lower portions, which are secured to the springs 98 by suitable clips 104. The upper transverse portions of the springs 98 and 100 have central loops 105 to increase the resiliency thereof. Preferably, these springs are of greater length than the main springs 90 so as to provide wings or extensions 106 which extend the side of the upholstered cushion 16 to a flush position with the rear of the back cushion 22, as best seen in Fig. 1. To round the corners of the cushion 16 prior to heat treatment, the semi-circular front portions 108 of the springs 98 are deflected inwardly into an arc and clamped to the springs 100 at 110 in the manner of the return bent portions 46 of the cushion 22.

Upper and lower border and spacing wires 112 corresponding to the wires 50, 52 and 54 are used at the front and rear of the spring structure of the cushion 16. These wires have longitudinal offset portions 114 and 116 connected by transverse portions 118. Clips 120 fasten the parts 118 to the springs 90, while hog rings 122 or other suitable structure secure the coil springs 96 to the portions 116. To supply support for the padding of the front edge 124 of the seat cushion 16, a mat of mattress wire 126 is suitably secured in place over the semi-circular front portion 128 of the springs 90 (see Figs. 7 and 14).

One satisfactory manner of securing the trim to the spring structure and for securing the seat cushion 16 to the seat frame 10 takes the form of longitudinal wires 130 and 132, to which the upholstery is hog ringed or otherwise suitably fastened, as shown in Fig. 4. The hog rings 134 are shown as piercing the upholstery and are suitably spaced along and embrace the wires 130 and 132, which arrangement has been found to be quite satisfactory, as the hog rings may be readily applied and removed as required. To fasten the seat cushion 16 to the frame 10 a suitable number of clamp bolts 136 are provided along the supporting flange 14 and engage over the wires 130 and 132 to removably fasten the cushion 16 in place. If found desirable for added support, one or more coil springs 140 may be positioned between the upper and lower portion of the end springs 98 and 100. This is likewise true with respect to the end springs 34 and 36 in the cushion 22.

With particular attention to Fig. 1, it will be

apparent that the spring structure of the cushion 16 is solely supported by the support afforded its outer edge portions by the continuous flange 14. As a result, the entire central portion of the 5 spring structure is free to deflect into the open base 10. This arrangement not only gives what I have chosen to call a "bottomless" seat but it also permits the free circulation of air into the 10 ported base 10 and into the interior of the spring structure of the seat cushion 16.

Another desirable characteristic of the spring structure of the cushions 16 and 22 resides in the fact that the spring structure is of the same 15 contour and dimensions before and after trimming. Also, of equal importance is the fact that the spring structure made up from the transverse loop springs and the compression coil springs, together with the longitudinal spacing elements, constitutes its own supporting frame structure 20 and does not require any auxiliary frame structure, as has been the practice heretofore in automobile cushions. For example, as will be clear from Fig. 6, the coil springs 96 tie adjacent portions 92 and 94 together by being hog ringed at 25 142 to each other. The undulations in the adjacent springs 92 and 94 are preferably in opposed relation so that by placing the hog rings at the apexes, shifting of the springs 24 and 90 is obviated.

30 In Figs. 9, 10 and 11 are shown several modified forms of the invention, in which the springs corresponding to the coil springs 30 and 96 have been omitted from the spring structure and other means provided for tying the transverse loop 35 springs together and affording adequate support to the padding. The construction of Fig. 9 is substantially that of Fig. 6 with the coil springs 96 and 140 omitted. In lieu thereof close wound helical springs 144 connected at opposite ends 40 have been used to provide a supporting surface for the padding in the plane of the upper portions 92 of the springs 90. The springs 144 also function to control the action of the portions 92 and tie the same into a more unitary supporting 45 framework. As shown, the springs 144 are only associated with the upper portions 92 of the springs 90. It is anticipated, however, that it might be desirable in some cases to similarly associate the springs 144 with the lower portions 50 94, particularly where the spring structure is relatively thin, so that the portions 92 will be deflected in normal use to the point of engagement with the portions 94. With such an arrangement, a suitable pad or the like would be inserted 55 between the portions 92 and 94 to eliminate noise. In the modification of Fig. 10 the mat 126 of mattress wire of Fig. 6 has been extended over the upper surface of the spring structure to provide a mat 146. As in the case of the mat 126, 60 the mat 146 is preferably woven from spring wire to impart resiliency to the structure. Control is afforded the portions 92 of the springs by hog ringing the same at 148 to the mat 146. Additional hog rings 150 support the mat 146 on 65 the spring structure. The mat 146 supports the padding, spaces the spring portions 92, and because of the fact that it is woven from spring wire affords substantial resilient support to the spring structure. The springs 152 of Fig. 11 correspond to the springs 90 except for a slightly 70 modified shape of undulation, which is particularly adaptable to the arrangement of the closely wound helical springs 154. The springs 154 correspond to and serve a function similar to the 75 springs 144 of Fig. 9.

In Fig. 12 springs 90 are shown spaced by and suspended from hour glass shaped coil springs 156 of well known construction in lieu of the covered coil type 30 and 96.

In Fig. 13 the spring structure of Fig. 9 is shown without the springs 144. Such a construction may be used where an extremely inexpensive seat is desired. Burlap and the like may be used to support the padding upon the upper portions of the spring 90. Also a suitable elongated padding 156, as indicated in dotted outline in Fig. 15, may be inserted between the upper and lower portions 92 and 94 of the springs 90 to eliminate noise that may be caused by these portions contacting each other upon extreme deflection of the portions 92. The padding will also function in a manner similar to the springs 30 and 96 in that a supporting load on the portions 92 upon deflection would be transmitted to the portions 94 as the padding is compressed. Such a pad may be like that disclosed in copending application Serial No. 206,565, filed May 7, 1938, by Donald E. Sargent.

Figs. 17 through 24 relate to various modified forms of loop spring constructions particularly adapted to the seat cushion. In Fig. 17 loops 158 and 160 are provided at the front and rear to soften the front and rear portions of the spring element. As more clearly shown in Fig. 18, the upper and lower undulated portions 162 and 166 of the spring elements 168 are out of phase with one another so that the lower portions 166 will offer a more reliable foundation for the absorption of a portion of the supported load upon substantial deflection of the upper portions 162. For increasing the pliability and regulating the feel and degree of support afforded to the occupant, numerous loops and return bends may be incorporated into the fabrication of the tension spring element. In Fig. 19 loops 170 and 172 are formed in the upper and lower portions 174 and 176. The number and location of these loops may be varied depending upon what results are desired. In Fig. 20 the loop 178 is located in the corner of the spring element, while the loop 180 is elongated to project the hinge point further inwardly than the loop 158, for example, of Fig. 17. With the same gauge wire the loop 180 would provide a softer front portion than the loop 158. A departure from the closed transverse loop spring is shown in Fig. 21, in which the spring element 182 has its ends 184 and 186 secured to a support upon a relatively rigid composite sheet metal and fibre tacking frame with a crimping flange 188. An enlarged loop 190 is provided at the front of the spring element, which produces a more yielding front with the same gauge wire and a more restricted loop 158.

The undulations in the loop spring elements heretofore described have one outstanding purpose, namely, to enable material deflection without noticeable transverse shortening or inward distortion of the spring element. While in most cases it will be preferable to have the undulations located in the general plane of the cushions, however, this is not necessary. In Fig. 22 the undulations 192 are in the plane of the upper element. Other arrangements will suggest themselves to those skilled in the art.

A perspective view of a further modification of the loop spring element for use in the seat cushion 16 is shown in Fig. 23. The front portion 194 has been softened and rendered more pliable by zig-zagging the wire back and forth.

Such a front construction affords support for the padding and a possible elimination of the mat 126 of Fig. 6. Along somewhat similar lines is a modification of Fig. 24, in which the compression spring portion 196 has been coiled as an integral part of the upper and lower portions 198 and 200 of the loop spring elements. An arrangement of this kind imparts a very desirable character of support to the front portion of the seat cushion, being relatively soft and resilient, yet at the same time affording adequate support to the thigh.

Referring to Figs. 26 and 27, I show a modified form of the spring element 24 of Fig. 25 used to construct the spring structure of the back cushion 22. Integral with the portions 202 and 204 are top and bottom portions 206 and 208 of the same general zig-zag construction as the front portion 194 of Fig. 23. In this manner a pliable back and lower edge of the back cushion may be obtained. As should be readily appreciated, the length and sharpness of bend of the zig-zag portion may be varied to increase or decrease the pliability with the same gauge wire.

25 In lieu of coiling the spring 196 integrally with the loop spring portions 198 and 200, the coil springs 210 (see Figs. 28 and 29) may be separately coiled and the ends 212 and 214 of the loop spring portions 216 and 218 suitably clipped 30 to the upper and lower convolutions.

The foregoing description has treated separately the spring structures of the seat cushion 16 and the back cushion 22, including the numerous modified forms of the spring elements 35 thereof. This has been done more as a matter of convenience than for any other reason and in view of the fact that the spring structure of each cushion is of substantially the same general construction and in some cases may be substantially 40 identical as well as being interchangeable. Moreover, in the numerous forms of the invention illustrated, various ways are shown for securing the desired characteristics of support, pliability, resiliency, etc. In some forms of the invention 45 two different methods are used in a single spring element, as, for example, in Fig. 24 a loop has been used at one end and an integral coil spring used at the other end of the loop spring element. Obviously, gauge of wire, support required and 50 other variables enter into the design of the cushion construction and will result in combinations being selected other than those illustrated. Accordingly, I do not wish to be limited to the specific constructions shown but desire to claim 55 the novel features of the invention as broadly as they are defined in the annexed claims.

I claim:

1. A spring structure designed to be upholstered comprising a marginal seat frame having 60 a generally open central portion, a plurality of transversely extending longitudinally spaced springs formed from resilient wire and generally shaped as elongated flat loops with the flat sides 65 thereof defining the upper and lower surfaces of the spring structure, longitudinally extending spacing members secured to said springs along the longitudinal edges of the spring structure, coil springs extending between the flattened sides 70 of said loops, the terminal convolutions of said coil springs being disposed in the planes of said flattened sides, and means clipping the adjacent flattened sides to said terminal convolutions, whereby said transverse springs are spaced in 75 said spring structure and all of said springs tied together into a unit, said first named springs

being supported adjacent the ends thereof by said marginal frame.

2. A spring structure designed to be upholstered comprising a marginal seat frame, a plurality of spaced springs formed from resilient wire and generally shaped as elongated flat loops with the flattened sides thereof defining the upper and lower surfaces of the spring structure, said springs being supported adjacent their ends in said frame and a plurality of coil springs positioned between the said flattened sides and compressible upon deflection of the upper flattened sides of said first springs to transmit the load to the lower flattened sides, whereby resilient support is afforded by both the upper and lower flattened sides of said first springs with said spring structure marginally supported.

3. The combination with a seat frame having a marginal supporting surface for a seat cushion and a generally open central portion bridged by the cushion, of an upholstered cushion spring structure having marginal support upon said seat frame supporting surface, said spring structure comprising a plurality of spaced upright springs formed from resilient wire and generally shaped as elongated flattened loops with the upper and lower flattened sides thereof defining the upper and lower surfaces of the spring structure, said springs being supported adjacent their ends in said frame, means for spacing and supporting said springs in their upright position so as to provide a self-contained spring structure, and resilient supporting means interposed between said flattened sides for transferring a portion of the load to the lower flattened sides, deflecting the same between the points of marginal support of the springs upon deflection of said upper sides.

4. The combination with a seat frame having a marginal supporting surface for a seat cushion and a generally open central portion bridged by said cushion, of an upholstered spring structure adapted to be directly supported upon said seat frame, said cushion having marginal support with said seat frame supporting surface, the central portion of said spring structure bridging the open central portion of said seat frame, a plurality of spaced spring members comprising spaced upper and lower resilient spring wire portions disposed in planes generally parallel to the supporting surface of the cushion, said lower portions bridging the central opening in said seat frame and having marginal support upon said seat frame, and means interposed between said upper and lower portions for resiliently supporting a portion of the supported load upon said upper portions upon deflection of the latter and functioning to transmit a portion of said load to said lower members to deflect the same into the central opening of said seat frame.

5. The combination with a seat frame having a marginal supporting surface and a central opening into which the cushion spring structure may be deflected, of a relatively thin upholstered cushion spring structure having marginal support upon the supporting surface of said seat frame with the central portion of said cushion spring structure bridging the central opening of said seat frame, said cushion spring structure comprising upper and lower spring elements defining the supporting surfaces thereof, said lower elements having marginal support upon said seat frame, and means interposed between said upper and lower elements for transferring a deflecting load from said upper elements to said lower elements, whereby the latter are deflected by said load into the central opening of said frame.

6. The combination with a seat frame having a marginal supporting surface for a seat cushion and a generally open central portion bridged by said cushion into which said cushion may deflect, of an upholstered cushion spring structure having marginal support upon said seat frame supporting surface, said spring structure comprising a plurality of transversely extending elongated spring elements in the form of flattened loops of substantial length, the flattened sides of said spring elements being undulated in a surface generally parallel to the supporting surface of the cushion spring structure, longitudinally extending spacing and bracing wires for said spring elements tying the same into a unitary self-supporting structure, and coiled compression springs having the terminal convolutions thereof disposed in the planes of said flattened sides, and means clipping said convolutions between opposed undulations of said sides.

7. The combination with a seat frame having a marginal supporting surface for a seat cushion and a generally open central portion bridged by said cushion into which said cushion may deflect, of an upholstered cushion spring structure having marginal support upon said seat frame supporting surface, said spring structure comprising a plurality of transversely extending elongated spring elements in the form of flattened loops of substantial length, the flattened sides of said spring elements being in a surface generally parallel to the supporting surface of the cushion spring structure, longitudinally extending spacing and bracing wires for said spring elements tying the same into a unitary self-supporting structure, and coiled compression springs having the terminal convolutions thereof disposed in the planes of said flattened sides, and means clipping said convolutions to said sides.

CLAIR S. REED.
